FORMING HEAD ARRANGEMENT

Frank E. Weller, Bloomfield, N. J.

Application October 23, 1936, Serial No. 107,273

11 Claims. (Cl. 117—16.5)

My invention relates to an arrangement or mechanism for manipulating either one or more single wires, or one or more strands, the latter comprising a plurality of wires disposed in helical formation but not necessarily set in said helical formation, the aforesaid single wires or strands being either circular or non-circular as desired.

My invention has more particular reference to 10 a manipulating arrangement, as aforesaid, constructed as a forming head utilizable for changing the form or for setting wires or strands.

My invention has further reference to various improved features of a forming head which 15 renders the same operable in a highly satisfactory manner for the manipulation of wires or strands in the manner noted.

Various other objects, advantages and characteristics of my invention will become apparent 20 from the following detailed description.

My invention resides in the arrangement, mechanism, forming head, features and advantages of the character hereinafter described and claimed.

This application is a continuation in part of my 25 pending application Serial No. 60,200, filed January 22, 1936.

For an understanding of my invention and for 30 an illustration of one of the many forms thereof, reference is to be had to the accompany drawings, in which:

Fig. 1 is an elevational view, partly in section, showing a forming head arrangement as constructed in accordance with my invention;

Fig. 2 is a front elevational view of the forming head arrangement shown in Fig. 1;

Fig. 3 is an enlarged elevational view, partly in section, of a spindle-supporting assembly as constructed in accordance with my invention;

Fig. 4 is a plan view of the arrangement shown 40 in Fig. 3;

Fig. 5 is a vertical sectional view, partly in elevation, showing the forming head arrangement of my invention;

Fig. 6 is an elevational view, partly in section, showing a modified spindle as constructed in accordance with my invention;

Figs. 7 and 8 are perspective views showing the spindle-supporting assembly of my invention;

Fig. 9 is an elevational view of a modified guiding slot arrangement for a wire or strand;

Fig. 10 is an elevational view showing another modified guiding slot arrangement for a wire or strand; and

Fig. 11 is an enlarged elevational view, partly in section, of a modified spindle-supporting assembly.

As shown on the drawings, the forming head of my invention comprises a main shaft 1 which is adapted to carry a front disk 2, a rear disk 3 and 60 a guide plate 4.

In accordance with a preferred form of the invention, the front disk 2 is secured in fixed position to the shaft 1, and the rear disk 3 is secured to said shaft 1 in such manner that it may readily be adjusted longitudinally, but not rotatably, 5 thereof.

To this end, as illustrated in Fig. 5, the shaft 1 may have its diameter at the end thereof reduced as shown at 1a so as to form a seat for the hub 2a of the disk 2, said hub 2a being maintained in 10 position by a nut member 5, and rotation of said hub 2a with respect to said shaft end 1a being suitably prevented, as by a key 6, Fig. 2, which is received in adjacent slotted portions of the hub 2a and the reduced shaft end 1a.

As shown in Figs. 1 and 5, the disk 3 is formed with a hub 3a having an internal diameter such that said hub may be freely moved longitudinally of the shaft 1 in the manner hereinafter described. Coactable with opposite faces of the hub 20 3a are the respective nut members 7 and 8 which are threaded to a threaded section 1b of the shaft 1. Rotation of the disk 3 on the shaft 1 is suitably prevented, as by a key 9 which is received in adjacent slotted portions of the hub 2a and said shaft 1. As will readily be understood, 25 one of the nuts 7, 8 may be loosened, whereupon the disk 3 may be moved longitudinally along the shaft 1 toward the loosened nut and then the other nut may be tightened so as to clamp said disk 3 in its position to which adjusted. The arrangement thus described constitutes a satisfactory means for adjusting the distance between the two disks 2 and 3 for the purpose hereinafter described.

As shown, the above noted guide plate 4 comprises a hub 4a which carries one or more clamping screws 10 utilized for positively retaining said guide plate 4 in an adjusted position on the shaft 1. Further, as shown, the guide plate 4 is 40 provided with a plurality of passages 4b distributed just within the periphery thereof.

In accordance with the invention, the hereinbefore described disks 2 and 3 are adapted to carry a plurality of spindles 11 which are suitably 45 spaced with respect to the shaft 1 outwardly of the periphery thereof. Each end of each spindle 11 is supported by a spindle-supporting assembly of novel construction as hereinafter to be described.

Thus, as shown particularly in Fig. 3, each spindle-supporting assembly comprises a set of coacting members 12 and 13, the adjacent faces of these members preferably being shaped as shown so as to form a seat for the reduced spindle 55 end 11a to be associated therewith.

As illustrated on the drawings, each of the disks 2 and 3 is provided with a plurality of slots 14 which, individually, are disposed diametrically of the respective disks 2, 3 or substantially so. Each 60

of the slots 14 snugly receives a spindle-supporting assembly, as aforesaid and, as clearly shown in Fig. 2, the slots 14 in both disks are in alignment, pair by pair, longitudinally of the main shaft 1. As illustrated in Figs. 3 and 4, the assembly members 12 and 13, at their outer edges, are provided with flanges 15 which serve to guide and retain the sets of assembly members 12, 13 in their respective slots 14.

10 Further, by reference to Figs. 3 and 4, it will be noted that the structure of either disk 2 or 3, immediately adjacent opposite faces of each slot 14, is provided with the respective threaded passages which receive the screws 16, respectively. Each 15 screw 16 is provided with a head 16a and, as shown in Figs. 3 and 4, a pair of these heads 16a coact with the adjacent upper surfaces of each assembly member 13. Further, the structure of either disk 2 or 3, at the bottom of each slot 14, 20 is provided with a threaded passage which, as shown in Fig. 5, receives a screw 17 having a head 17a coactable with the adjacent face of the assembly member 12. The reasons leading to the provision of the adjusting arrangement comprising 25 the screws 16 and 17 will be hereinafter referred to in detail.

In accordance with the invention, each of the upper members 13 of the various spindle-supporting assemblies serves as a guide for a wire or strand. To this end, each member 13, is formed 30 with an open slot 13a extending approximately longitudinally of the shaft 1. Further, as shown, one side wall 13b of the slot 13a preferably is curved as shown in Fig. 4 while the opposite side 35 wall 13c preferably is plane.

35 In operation, a single wire or a strand W is threaded through each of the passages 4b of the guide plate 4, through each slot 13a of the respective members 13 of the disk 3, passed once 40 around each spindle 11 as shown in Fig. 1, and then through each slot 13a of the respective members 13 of the disk 2, all of the wires or strands W then passing through the usual sizing die 18, Fig. 1, so that said wires or strands may be properly 45 positioned on the core W1 which passes through the center of the main shaft 1. After the guide plate 4 has been adjusted to a desired rotated position circumferentially of the shaft 1 so as to cause the wires or strands to enter the slots 13a of the disk 3 in proper angular relation, the forming 50 head arrangement is caused to rotate at proper speed by power applied to the shaft 1 and the usual drum mechanism beyond the die 18 is placed in operation to cause the wires or strands 55 W and the core W1 to be drawn first through the forming head arrangement herein described and then through the die 18.

As clearly appears from a consideration of Fig. 1, the single wires or strands W, by reason of the 60 fact that they are drawn around the respective spindles 11 under tension, are shaped or given a set configuration as indicated at 3, Fig. 1. Accordingly, the single wires or strands as thus shaped or set, when drawn through the sizing die 65 18, more or less automatically assume their proper positions, respectively, so as to form the cable C. With the form of the invention herein illustrated, the strands W, beyond the forming head arrangement, are actual strands and they are illustrated 70 as of "regular lay" configuration. As well, it will be understood, said last named strands, beyond said forming head arrangement, may be of the "lang lay" configuration if desired. Further, it will be understood, depending on the positions of 75 the members or inserts 13 in their respective slots,

that the lay may be either right or left as desired. Thus, if a member or insert 13 is associated with the rear disk 3 when positioned as shown in Fig. 7 and another member or insert 13 is associated with the front disk 2 when positioned as shown in Fig. 8, a right lay wire or strand is produced. If a member or insert 13 is associated with the front disk 2 when positioned as shown in Fig. 7 and another member or insert 13 is associated with the rear disk 3 when positioned as shown in Fig. 8, a 10 left lay wire or strand is produced.

As hereinbefore stated, the disk 3 may be moved either toward or from the disk 2 by unloosening the nut member 7 or 8 and then tightening the unloosened nut member against the 15 face of the disk hub 3a. As will readily be understood, this may be done while the single wires or strands W are operably associated with the respective spindles 11 but, preferably, after said single wires or strands W have been slackened 20 to some extent at the left of the disk 3. By so doing, the "lay" or pitch of said wires or strands W may be decreased or increased to thereby facilitate the proper positioning of the shaped or set wires or strands in cable or rope formation C 25 at the sizing die 18.

An adjusting operation of the character described above is performed in those cases when the "lay" or pitch of the wires or strands is to be decreased or increased to a slight extent. If 30 the "lay" or pitch is to be decreased or increased substantially, or if the helix diameter is to be changed, it becomes necessary to substitute a new set of spindles 11 for those already in the forming head. This is done by widely separating 35 the disk 3 from the disk 2, then substituting one set of spindles for the other and then returning the disk 3 to its operative position. Before doing this, the wires or strands W at the left of disk 3 should be slackened, then the sections of said 40 wires or strands in the slots 13a of the members 13 are moved therefrom and placed upon adjacent surfaces of the disks 2 and 3, for example. At this time, one set of spindles may be substituted for the other set whereupon the wires or 45 strands may again be placed in operative position with the slots 13a and with respect to the respective spindles 11. The foregoing may be accomplished by virtue of the utilization of the open-slot members 13. The provision of these 50 members, then, is of importance in accordance with the invention because, if they were not provided, it would probably be necessary to cut the wires or strands when substituting one set of spindles for another. Moreover, these open-slot 55 members 13 are of distinct importance in connection with the initial threading of the forming head.

As regards the form of the invention hereinbefore described in connection with Figs. 1-5 60 inc., each end 11a of a spindle 11 has a suitable bearing arrangement, including a thrust washer 20, between the members 12, 13 of any spindle-supporting assembly so that said spindles 11 are freely rotatable under the influence of the 65 respective wires or strands W which are shaped thereon. This is a feature of decided importance in connection with my invention because decreasing the abrasive effect of the spindles on the respective wires or strands W, because decreasing 70 wear of the spindles, and because decreasing the power required for passing wires or strands through the forming head arrangement. These, as will be understood, are features of importance 75 in connection with my invention. Further, in 75

connection with an arrangement of this character and as shown in Fig. 5, the reduced ends 11a of the spindles 11 should be of such length that the above noted adjustments of the disk 3 may readily be effected without rendering the rotatable bearings for the various spindles unsatisfactory from an operating view point.

Under some circumstances, the spindles 11 may be of the non-rotatable type in which case an arrangement of the character shown in Fig. 6 may be employed. Thus, each end 11b of a spindle 11 of Fig. 6 may be of square or other suitable configuration, such end being received in a corresponding seat between the members 12, 13 of the spindle-supporting assembly.

As stated, the inserts or members 13 of the spindle-supporting or -bearing assemblies are detachable from the slots 14, this being readily accomplished after the various screws 16 have been removed. This is highly advantageous because these members 13, at their curved surfaces 13b, take the abrasive wear of the wires or strands. Even though formed of suitable wear-resisting material, they are subject to considerable wear and must be replaced at times, this, obviously being accomplished in a ready manner as stated.

Further, as disclosed, the bottom surface of each slot 13a of an insert member 13 is disposed, preferably, substantially flush with respect to the peripheral surfaces of the respective spindles 11. This is advantageous because facilitating the proper passage of the wires or strands along the spindles 11.

The hereinbefore described screws 16 may be retracted whereupon the screws 17 may be operated to change the position of the spindle bearing assemblies in their respective slots as desired. In so doing, the spindles 11 are moved either toward or from the shaft 1 without any substantial change in the inclination of said spindles. This is done so that the shaped wires or strands automatically take the proper positions in the sizing zone, the arrangement rendering this adjustment possible being of distinct importance in connection with the invention. The adjustment of the spindles 11 as just described is accomplished advantageously by reason of the provision of the aligned pairs of slots 14 in the respective disks 2 and 3, the slots 14 of each pair of slots being inclined and disposed in substantially parallel relation so as to provide parallel, inclined trackways for movement of the bearing assemblies under the control of the respective screws 17.

As herein disclosed, the disks 2, 3 are of dish formation and, therefore, the above noted pairs of parallel, inclined slots 14 may readily be provided. In addition, as will be noted, each of the disks 2, 3 is provided with a plurality of strengthening ribs 23 disposed on the front disk surfaces so as to resist fracture of the disks when subjected to the strain of the wires or strands undergoing the setting operation. By virtue of the provision of these ribs 23, the disks 2 and 3 may be maintained at minimum thinness with the result that the slots 13a may be of minimum length to thereby decrease friction, wear, etc.

In order further to decrease friction and wear, each insert or member 13 may comprise a roller 21 of wear-resisting metal, Fig. 9, this roller being disposed at a suitable angle, for example, a right angle to the path of travel of the wire or strand which engages therewith. Alternatively, further to reduce friction and for other desirable purposes, a roller 22 having a curved, sloping

face such, for example, as illustrated in Fig. 10 may be associated with each insert 13.

In Fig. 11, I have illustrated a modified form of spindle-supporting or -bearing assembly adapted particularly for association with each slot 14 of the front disk 2 although, if desired, spindle-supporting assemblies such as illustrated in Fig. 11 may be associated with the respective slots 14 of the rear disk 3. As shown in Fig. 11, the modified spindle-supporting assembly comprises upper and lower members 24 and 25. The upper member 24 may comprise either a right or left slot 24a and, if desired, a roller 21, 22 or equivalent as hereinbefore described may be associated with said slot 24a. The lower member 25 is formed with a plurality of circular recesses 25a having cooperative therewith a circular tooth or pin 26 upstanding from the head 17a of the adjusting screw 17. Positioning pins 27 are associated with the members 24, 25 and said upper member 24 comprises opposite flattened sections with which the respective screw heads 16a coact.

With the arrangement of Fig. 11, the screws 16 may be retracted whereupon the members 24, 25 may be elevated from the tooth 26 and partially rotated in one direction or the other. Then, said members 24, 25 may be re-seated, a different recess 25a receiving the tooth 26, and the screws 16 returned to clamping position. In this manner, the spindle-supporting assembly may be clamped in a desired position circumferentially of the associated spindle 11.

Assuming that the end slot 14 of the front disk 2 is equipped with a spindle-supporting assembly as illustrated in Fig. 11, one or more of these assemblies may be adjusted as just described to increase or decrease the helix diameter and to somewhat change the path of travel of one or more of the single wires or strands W whereby the various single wires or strands assume a better fitting relation just prior to or at the time that they enter the die 18. An arrangement of the character illustrated in Fig. 11 is useful particularly in connection with non-circular single wires or strands although such an arrangement is also useful with circular single wires or strands.

As shown in Fig. 2, it is desirable that the front face of the disk 2 exhibit a plurality of 50 concentrically arranged marks 28 which are segments of circles concentric with respect to the shaft 1. These marks 28 may be calibrated in a predetermined manner so as to assist the operator when adjusting the spindles 11 under the control of the respective screws 17.

When an adjustment is effected by movement of the disk 3 either toward or from the disk 2 as hereinbefore described, it will be understood that the various screws 16 should be retracted to some extent so as to permit the spindle-supporting assemblies to take new non-binding positions and, before operation of the machine is resumed, the screws 17 and 16 should be tightened to positively retain the respective spindle-supporting assemblies in proper bearing positions. It will be understood that adjusting operations of the character just described are important in connection with the spindle-supporting assemblies associated with the disk 3 and, likewise, such 70 adjustments may be important in connection with the spindle-supporting assemblies for the disk 2.

The arrangements of my invention are particularly useful in connection with the shaping or 75

setting of circular or generally circular wires or strands. However, the invention is not to be thus limited because, in an advantageous manner, the open slot arrangement of the inserts 13 and the spindles associated therewith cooperate for the desirable control of three-corner, flat, or strands or wires of other shapes. Further, the rollers of Figs. 9 and 10 function in a satisfactory manner for the control of strands or wires of the configuration just described.

It will be understood that the forming head arrangement of my invention may be adapted for the shaping or setting of any desired number of wires or strands. As herein illustrated, there are six spindles and a corresponding number of bearing assemblies for each spindle end. As well, if desired, a greater or less number of spindles may be utilized as desired.

While the invention has been described with respect to certain particular preferred examples which give satisfactory results, it will be understood by those skilled in the art after understanding the invention, that various changes and modifications may be made without departing from the spirit and scope of the invention and it is intended, therefore, in the appended claims to cover all such changes and modifications.

What is claimed as new and desired to be secured by Letters Patent is:

- 30 1. In a head utilizable for the manipulation of single wires or strands, a main shaft, front and rear disks secured thereto in spaced relation, spindles rotatably carried by said disks for shaping the respective single wires or strands, means for adjusting one disk along said shaft with respect to the other disk while said spindles remain operatively associated therewith, and means for adjusting the bearings for said spindles radially with respect to said shaft.
- 40 2. In a head utilizable for the manipulation of single wires or strands, a main shaft, front and rear disks secured thereto in spaced relation, a spindle carried by said disks for shaping a single wire or strand, and members detachably carried by the respective disks at opposite ends of said spindle, said members taking the abrasive action of said wires or strands as the latter approach and leave said spindle.
- 50 3. In a head utilizable for the manipulation of single wires or strands, a main shaft, front and rear disks secured thereto in spaced relation, a spindle carried by said disks for shaping a single wire or strand, and members carried by the respective disks at opposite ends of said spindle, each of said members being provided with a slot having an open side at or adjacent the periphery of its supporting disk.
- 60 4. In a head utilizable for the manipulation of single wires or strands, a main shaft, front and rear disks secured thereto in spaced relation, a spindle carried by said disks for shaping a single wire or strand, and members carried by the respective disks at opposite ends of said spindle, each of said members being provided with a slot having an open side at or adjacent the periphery of its supporting disk, the bottom of each slot being substantially flush with respect to the spindle surface.
- 70 5. In a head utilizable for the manipulation of single wires or strands, a main shaft, front and rear disks secured thereto in spaced relation, a

spindle carried by said disks for shaping a single wire or strand, and bearing assemblies carried by the respective disks at opposite ends of said spindle, each bearing assembly comprising a member provided with a slot for the passage therethrough of a single wire or strand.

6. In a head utilizable for the manipulation of single wires or strands, a main shaft, front and rear disks secured thereto in spaced relation, a spindle carried by said disks for shaping a single wire or strand, bearing assemblies carried by the respective disks at opposite ends of said spindle, and means for adjusting each bearing assembly toward or from said main shaft.

7. In a head utilizable for the manipulation of single wires or strands, a main shaft, front and rear disks secured thereto in spaced relation, a spindle carried by said disks for shaping a single wire or strand, bearing assemblies carried by the respective disks for supporting the opposite ends of said spindle respectively, and means whereby each bearing assembly may be adjusted along a path toward or from said shaft, said paths being disposed in substantially parallel relation.

8. In a head utilizable for the manipulation of single wires or strands, a main shaft, front and rear disks secured thereto in spaced relation, inclined spindles carried by said disks for shaping the respective single wires or strands, said spindles being rotatable on their respective longitudinal axes so as to decrease the abrasive effect of the spindles on the respective single wires or strands and vice versa.

9. In a head utilizable for the manipulation of single wires or strands, a main shaft, front and rear disks secured thereto in spaced relation, a spindle carried by said disks and inclined with respect to said shaft for shaping a single wire or strand, and means for moving said spindle bodily toward or from said shaft while maintaining substantially constant the inclination of said spindle with respect to said shaft.

10. In a head utilizable for the manipulation of single wires or strands, a main shaft, front and rear disks secured thereto in spaced relation, a spindle carried by said disks and inclined with respect to said shaft for shaping a single wire or strand, slots disposed within the periphery of the respective disks for guiding the single wire or strand toward and from said spindle, each of said slots having an open side at or adjacent the periphery of its supporting disk, the slots in the respective disks being aligned in pairs substantially longitudinally of said shaft, and a plurality of ribs disposed on one face of each disk to thereby strengthen the same so that the disk thickness and the length of said slots may be at a minimum.

11. In a head utilizable for the manipulation of single wires or strands, a main shaft, front and rear disks secured thereto in spaced relation, a spindle carried by said disks for shaping a single wire or strand, and an assembly carried by the front disk for bearing or supporting the adjacent end of said spindle, said assembly comprising a member provided with a slot for the passage therethrough of a single wire or strand, and means for adjusting said assembly circumferentially of said spindle.
